UNITED STATES PATENT OFFICE.

PAUL J. NEITZEL, OF SOUTH BEND, INDIANA.

DESIGN FOR A GAME-BOARD.

SPECIFICATION forming part of Design No. 34,457, dated April 30, 1901.

Application filed January 28, 1901. Serial No. 45,150. Term of patent 14 years.

To all whom it may concern:

Be it known that I, PAUL J. NEITZEL, a citizen of the United States, residing at South Bend, in the county of St. Joseph and State of Indiana, have invented and produced a new and original Design for a Game-Board; and I do hereby declare the following to be a full, clear, and exact description of the same, reference being had to the accompanying drawings, forming a part thereof.

My invention relates to a new and original design for game-boards, and the object is to provide one which will be useful as well as ornamental.

The essential feature of the design resides in providing the game-board on its surface with a series of concentric squares, the central one having pins at its corners and the intermediate one provided with pins diametrically arranged, the intermediate square being divided in four parts by the diametrical lines drawn from its pins to the edge of the central square.

Another feature of the design resides in providing two concentric circles upon the face of the board near its outer edges inclosed by truncated triangles, the hypotenuse of the triangles being concaved or curved inwardly, there being four such circles and triangles, each of which is arranged intermediate of the corners of the board.

In the drawings, Figure 1 is a perspective view of the game-board, and Fig. 2 is a top plan view.

1 represents the face of the board, having 35 marked thereon a series of concentrically-arranged squares 2, 3, and 4, the outer square 4 being parallel to the outer edge of the board as are all the others parallel to it. At each corner of the central square pins 5 are secured and project upwardly from the face of the board.

6 indicates pins arranged at diametrical points on the square 3 and from which pins are marked off the diameters of the square 3, 45 but which terminate at the sides of the central square 2, thus forming four divisions of the square 3, the inner corners of which are overlapped by the square 2. A suitable bead 7 is provided upon the edge of the board and projects upward from the face thereof. Extending from the bead 7 are the truncated triangles having the concaved hypotenuse, and within this triangle are two concentric circles 9, divided into sections by diametrical 55 lines, as shown.

Having thus described my invention, what I claim is—

The design for a game-board substantially as shown and described. 60

In testimony whereof I affix my signature in presence of two witnesses.

PAUL J. NEITZEL.
